UNITED STATES PATENT OFFICE.

LOUIS KRANZ, OF PROVIDENCE, RHODE ISLAND, ASSIGNOR TO THE WAITE, THRESHER COMPANY, OF SAME PLACE.

DESIGN FOR A HANDLE FOR BUTTON-HOOKS, &c.

SPECIFICATION forming part of Design No. 28,919, dated June 28, 1898.

Application filed May 23, 1898. Serial No. 681,519. Term of patent 3½ years.

To all whom it may concern:

Be it known that I, LOUIS KRANZ, a citizen of the United States, residing at Providence, in the county of Providence and State of Rhode Island, have invented and produced a certain new and original Design for Handles for Button-Hooks or Similar Articles; and I do declare the following to be a full, clear, and exact description of the invention, such as will enable others skilled in the art to which it appertains to make and use the same.

The invention relates to a new and original design for handles for button-hooks or similar articles; and it consists of a design of the configuration and ornamentation shown in the accompanying drawing, in which I have illustrated my invention in plan view.

The leading features of the design consist of the body portion 1, provided with the heraldic shield 2, surrounded by fanciful scrolls

3, which are surmounted by a crown-piece 4. Below the shield are two curved elongated bodies 5, provided with curved rows of beads 6. Below the beads 6 is a curved plane surface 7, surrounded by a scrollwork 8, and below the scrollwork 8 is an acorn and leaf 9, and below these are the upwardly-projecting leaves 10.

What I claim is—

The design for the handle of a button-hook or other similar article as herein shown and described.

In testimony whereof I have hereunto set my hand in presence of two subscribing witnesses.

LOUIS KRANZ.
